(57) **CLAIM**

The ornamental design for a table, as shown and described.

DESCRIPTION

FIG. 1 is a perspective view of my table;

FIG. 2 is a front elevational view thereof;

FIG. 3 is a left side view thereof;

FIG. 4 is a rear elevational view thereof;

FIG. 5 is a right side view thereof;

FIG. 6 is a top view thereof; and,

FIG. 7 is a front elevational detail of the top corner portion of my table illustrating the ornamentation thereon in enlarged detail.

The broken lines are for environmental purposes only and form no part of the claimed design.
